(57) **CLAIM**

The ornamental design for a razor, as shown and described.

DESCRIPTION

FIG. 1 is a front elevation view of a razor, showing my new design;

FIG. 2 is a top plan view thereof;

FIG. 3 is a bottom plan view thereof;

FIG. 4 is a rear elevation view thereof;

FIG. 5 is a left side elevation view thereof;

FIG. 6 is a right side elevation view thereof; and,

FIG. 7 is a perspective view thereof.

In the drawings, the broken lines illustrate portions of the razor which forms no part of the claimed design.
